UNITED STATES PATENT OFFICE.

FREDERICK JOHN CHAMBERS, OF LONDON, ENGLAND, ASSIGNOR OF ONE-HALF TO
LEONARD ALAN LEGGATT, OF LONDON, ENGLAND.

ELECTROMAGNETIC WAVE RECEIVING AND AMPLIFYING SYSTEM.

Application filed December 13, 1922. Serial No. 606,583.

To all whom it may concern:

Be it known that I, FREDERICK JOHN CHAMBERS, residing at 48 Redcliffe Road, London, S. W. 10, England, have invented 5 certain new and useful Improvements in and Relating to Electromagnetic Wave Receiving and Amplifying Systems, of which the following is a specification.

The present invention relates to improvements in or relating to electromagnetic wave receiving and amplifying systems, more particularly to those systems which employ thermionic tube elements, and has for its object the provision of an improved circuit arrangement for use in connection with such tube elements.

The principal feature of the invention consists in the provision of an anode circuit comprising an inductive resistance and 20 two condensers all in series with the anode battery, the anode being connected to the junction point of the inductive resistance and the condensers while the filament is connected to the junction point of the condensers and anode battery, the outgoing oscillations being led from the terminals of one of said condensers while the incoming oscillations are led directly and independently of the anode circuit to the terminals 25 of the filament and grid. This circuit is adaptable and may have its constants of such value as to be oscillatory at the lowest frequency while at the same time remaining suitable as regards retro-active effects 30 through the valve, the incoming oscillations are led into a circuit connected between the grid and the filament which circuit is coupled to the anode circuit in the preferred form solely through the valve. 35 In fact this is always the case except in a cascade arrangement where the inductance in the anode circuit of the second valve may be coupled to the inductance in the anode circuit of the first valve as will be described 40 more fully hereinafter.

In known devices the resistance and the capacity between the grid and filament of the usual type of valve has barred the possibility of useful oscillation at low radio 45 and audio frequencies and this advantage is achieved by the present invention, more especially due to the insertion of capacity across the valve in series with inductance and resistance in the circuit of the anode 50 battery.

The anode battery is connected through an inductance a resistance or both to the anode. As the variations of voltage across the condensers will be inversely proportioned to their capacities, one condenser is 60 usually made of considerably greater capacity than the other and it is from across the terminals of the smaller condenser that the outgoing oscillations are taken. The capacities of the condensers are suitably 65 selected with respect to the inductance and resistance in the anode circuit in accordance with the particular use to which the arrangement is put.

Such applications of the invention will 70 be better understood by referring to the accompanying drawings, in which Fig. 1 illustrates the invention as applied to a combined detector and amplifier, with means for making the circuits selective or 75 non-selective as desired, while Fig. 2 shows a modification showing only one thermionic tube element, which is designed to both detect and amplify in itself.

As regards Fig. 1 it should be mentioned 80 that the circuit is designed for various uses which will be described later.

The thermionic tube elements are shown in the usual conventional form, the filaments being arranged in parallel and fed from 85 a small battery B through an adjustable resistance AR. The anode battery B¹ is connected with its negative pole to one side of the filaments and its positive pole to the anodes of the different valves 1, 2 and 90 3. In the first case through a resistance R¹ and an inductance I¹ and in the second case through a resistance R² and an inductance I², and in the third case through a telephonic receiver HR. The incoming oscillations which come from an antenna or any other suitable source are applied between 95 the grid and the filament of the first valve. Across the first valve are condensers C¹, c¹ in series; across the second valve are two 100 condensers C², c², also in series. The values of the resistances, inductances and condensers vary according as to what the system is to be used for, being readily chosen by those versed in the art of wireless telegraph and telephone design. Preferably 105 the first valve would be arranged to act principally as a detector, and the second valve and third valve as amplifiers, although this is not essential as the first 110

valve could be used as an amplifier, the second valve as a detector and the third valve as an amplifier.

The capacity of the condenser C^1 , and 5 C^2 should be such as to offer a low reactance to the resultant oscillations in the anode circuit of the first and second valves respectively, while the capacity of the condensers c^1 , c^2 should be of a considerably lower 10 value. The reactance of the condensers c^1 , c^2 should be low and will therefore be larger for a low frequency than for a high frequency. The value of this reactance will 15 determine the damping of the circuit due to the discharge from grid to filament in the second and third valves respectively, and it has not hitherto been appreciated that the damping factor attributable to this cause in the modern amplifying valves is an extremely 20 important matter when dealing with audible and even low radio frequencies. The reactance of this condenser should therefore be in proper relation to the resistance of the grid-filament path, having regard to the degree 25 of damping which is desired. It is understood of course, that the number of valves is only shown by way of example in Fig. 1 and any other number than three can be employed as may be desired. The receiver HR in that case would of course be always connected up in the anode circuit of the last valve of the series. Oscillations applied to the grid of the first valve are not instantly reproduced in similar but amplified 30 form at the grid of the succeeding valve, as such conditions cannot be reached until the expiration of the transitory period during which the proportion of energy storage in the several circuit components is automatically 35 readjusted to the imposed conditions. Again the induced effects do not cease simultaneously with the applied oscillations, as there must again be a re-distribution of stored energy before the stable conditions 40 are reached. In most known forms of amplifier circuits, these changes are generally accomplished by a compound oscillation containing a number of component frequencies attributable respectively to the various 45 circuits traversed, but in the present case in view of the simplified circuit arrangements for transient oscillations may be reduced to a simple wave form, and may be arranged to augment desirably the amplification.

When the trains of applied oscillations are short as for instance in receiving "Spark" signals or continuous wave "Morse" signals 50 on long wave-lengths, the transient oscillations may be extremely important. According to the values of the circuit constants, the amplitude of the transient effects may in such cases be much greater and those may persist much longer than the forced effects.

It is desirable, however, for certain purposes, to suppress the transient effects, for reducing, for instance, the effects of ionic irregularities in the valves or atmospherics, or in high speed reception where the trains 70 contain few oscillations, and it is necessary to reproduce these comparatively faithfully for recording instruments. Consequently the circuit constants must be so chosen as to regulate the nature and amplitude of the 75 transient oscillations so as to suit the purpose for which the amplifying apparatus is intended.

As an illustration of the transient phenomena, a simple case will be taken when the grid 80 of the first valve becomes slightly negative on the reception of an impulse. In that case some of the stored energy must be discharged from the field of the inductance I^1 connected to its anode before the anode current can fall to the value determined by the characteristic of the said valve. This energy will be principally transferred to the condenser c^1 and will set up oscillations of potential between the grid and the filament 90 of the second valve. This effect will be termed "the inductance effect." Moreover, if there is an appreciable resistance in the windings of the anode inductance I^1 as compared with the internal resistance of the anode filament path, or if resistance, such as R^1 of a similar value be inserted in the anode leads, a certain additional charge must be conveyed to the condensers C^1 , c^1 in order to raise the difference of potential between these 100 points to the new value determined by the valve characteristics. This effect will be termed "the capacitance effect." On the other hand, in the case of the grid of the first valve becoming slightly positive on the reception of an impulse, as the battery current through the valve will tend to increase, there would be naturally some delay due to the fact that the field of the inductance has to be first built up. A certain amount of the energy on the condenser is therefore discharged through the valve. This will be referred to as "the positive effect." By suitably choosing the constants of the circuit so that the product of the resultant capacity of the two condensers in series and the resistance of the valve and also the inductance divided by the resistance in the anode circuit are both 110 comparatively high compared with the duration of an oscillation, the units being henrys, farads, ohms and seconds, and when the valve circuits are preferably adjusted to have a natural frequency considerably lower than the applied oscillations, then high frequency oscillations are rectified and may be detected as is shown for example in Fig. 2, the receiver HR being connected across the condenser c^1 . Preferably I^1 is a very large inductance so that the negative grid impulses give c^1 a positive potential, and if 115 120 125 130

c^1 is large cannot be discharged in the short intervals when the grid is positive, and the result is that the potential on c^1 rises during a train of impulses and restores on completion of the train. Of course, the same remarks apply to the first valve of Fig. 1 if this is to detect. The advantage of this kind of rectification over known methods is that the smallest impulse is rectified so that it is not necessary to amplify weak signals before rectification.

The following values have been found to give highly satisfactory results. The inductance I^1 —30 henries, resistance R^1 — 10^5 ohms, capacity of condensers C^1 , c^1 in series 19^9 farads, valve resistance 3×10^5 ohms. It will be seen in this example that CR^V and L/R^1 are both equal to 3×10^4 seconds which is considerably larger than the duration of any radio frequency oscillation. It will also be recognized that the natural period of this circuit is of audio frequency.

If it is desired to employ a circuit such as shown in Fig. 1 for selectivity to impulses of predetermined frequency or duration, the time constant of the valve circuits may be regulated by inserting non-inductive resistances r^1 , r^2 , either in series with the condensers or as leakage shunts. Alternately grid potentiometers may be employed for this purpose. When selectivity is desired the resistances R^1 , R^2 should be kept low, and the shunt resistances r^1 , r^2 high. For this reason the switches S^1 , S^2 , s^1 , s^2 are provided, although if desired adjustable resistances or a number of resistances controlled by separate switches could be employed to give a greater range of adjustment. By this means the time constants of the discharge circuit may be adjusted so as to be long compared with the duration of a single impulse. If on the other hand it is not desirable that the system should be selective, as for instance in amplifying speech waves, or in designing amplifiers to be effective over a wide range of frequencies, means as above described may be employed to reduce the time constant, but it is not desirable to carry these beyond the point when the time constant of the discharge circuit is comparable with the duration of an individual impulse, unless the requirements are exceptional as for instance, when it is intended to eliminate the transient effects altogether, and employ only the forced effects.

The circuit consisting of the anode inductance, the two condensers and the anode battery in series may be tuned to the impulse frequency or to some multiple of this or a higher frequency if the impulses are of short duration compared with the time impulse between them. The above mentioned inductance may if desired, be that which will thus tune the discharge circuit,

and for this purpose may be made variable, the condensers may also be made variable if desirable or convenient. For stability condensers C^1 , C^2 , c^1 , c^2 may be shunted by high resistance leakage paths.

One advantage of the construction, according to the invention is that the possibility of retraction is practically eliminated, and if the inductances I^1 , I^2 are high, battery disturbances will be reduced to a minimum. For this reason in audio-frequency work, the inductances I^1 and I^2 are provided with iron cores, and the inductance may be as high as 30 henries or even higher.

If a cascade of three or more valves is connected in the manner described the anode inductances may be suitably coupled together, the two oscillating circuits will then react upon each other and tend to produce a cumulative effect, the extent of which is affected by the coupling, and the relation between their two natural frequencies. In this manner, according to a further feature of the invention, circuit arrangements may be set up which enable a small impulse applied to the grid of the first valve to bring into play a much larger amount of energy. If therefore, a suitable recording instrument or relay be inserted in the anode circuit of the third or succeeding valve, a small impulse or succession of small impulses may be caused to actuate an instrument requiring a comparatively large amount of energy for its operation.

Again using an arrangement similar to that just described and tuning the anode circuits of two valves to one another, and preferably also to the frequency of the applied oscillations or to a multiple or sub-multiple of such frequency, it will be found that there will be an interchange of energy between the two circuits which will give rise to beats at intervals which are determined almost entirely by the degree of coupling between them. By such an arrangement, according to the invention, continuous oscillations may be detected without having recourse to the well-known "heterodyne" method, which consists in superimposing a continuous oscillation of slightly different frequency upon that received from a transmitting station. In order that the beat frequency may be varied at will by the operator, the coupling between the circuits may be made variable. The sense in which the two circuits are coupled in order to interact may be that opposed to the generation of continuous oscillations in the well known manner. Clearly the same results may be obtained by an electrical coupling or by the use of resistances.

An audio frequency amplifier can be arranged so as to utilize the surge or transient effects to supplement the forced effects. In this case the resistance R in the anode cir-

cuit is comparable with the resistance between the anode and the filament.

The capacitance effect above referred to can be best represented by the following:—

5. Assume e_0 =initial potential across valve.

R_o =valve resistance.

R_A =resistance in anode circuit,

E =voltage of anode battery,

then

$$10 \quad e_0 = \frac{ER_o}{R_A + R_o}$$

On a negative impulse it will be assumed that

15. R_o changes to R_t

then

$$e_t = \frac{ER_t}{R_A + R_t}$$

20. Then the energy involved=

$$\frac{1}{2}C(e_t^2 - e_0^2)$$

25. Where C is capacity of condensers C^1 and c^1 in series,

The inductance effect on the other hand involves an amount of energy equal to

$$30 \quad \frac{1}{2}L(i_0^2 - i_t^2)$$

Where i_0 is initial current i_t is ultimate current.

35. L =inductance of I^1 .

$$i_0 = \frac{E}{R_A + R_o}$$

and

$$i_t = \frac{E}{R_A + R_t}$$

40. By employing circuit constants which ensure a comparatively low damping co-efficient, then charging current of the condensers C^1, c^1 from the battery B^1 will be of an oscillatory nature; and by making the resultant capacitance effect of the condensers C^1, c^1 in series predominating as regards the inductance effect, then if a negative impulse

45. applied between the grid and filament persists for sufficient time, the amplified voltage across the condensers may be nearly doubled; consequently, if the circuit including B^1, R^1, I, C^1, c^1 is tuned to twice the frequency of the applied impulses, the "transient" effects will appreciably supplement

50. the "forced" effects. In this way a highly efficient amplifier is obtained. If high frequency oscillations are applied, this arrangement serves equally well as a rectifier, for the radio frequency currents as referred to previously.

55. A second advantageous effect is obtained if the frequency of the applied audible frequency currents are the same frequency as

the natural frequency of the amplifier circuits. This will depend upon the value of the inductance I , and the effect of positive impulses applied to the valve. By using suitably proportioned circuit components, 70 very useful results can be obtained with speech currents without damping the circuits too highly.

What I claim and desire to protect by Letters Patent is:—

75. 1. A receiving arrangement for electrical oscillations comprising a source of electrical oscillations, a thermionic valve having a filament, a grid, and an anode, a circuit connecting said source of electrical oscillations between said filament and said grid, a battery, an oscillatory anode circuit comprising an inductive resistance, connected between said battery and said anode, the other terminal of said battery being connected to said filament, and two condensers in series connected between said anode and said filament and a receiving device connected across the terminals of one of said condensers.

80. 2. A receiving arrangement for electrical oscillations comprising a source of electrical oscillations, a thermionic valve having a filament, a grid and an anode, a circuit connecting said source of electrical oscillations between said filament and said grid, a battery, 85 oscillatory anode circuits comprising an inductive resistance connected between said battery and said anode the other terminal of said battery being connected to said filament, and two condensers in series connected between said anode and said filament and a receiving device connected across the terminals of one of said condensers.

85. 2. A receiving arrangement for electrical oscillations comprising a source of electrical oscillations, a thermionic valve having a filament, a grid and an anode, a circuit connecting said source of electrical oscillations between said filament and said grid, a battery, oscillatory anode circuits comprising an inductive resistance connected between said battery and said anode the other terminal of said battery being connected to said filament, and two condensers in series 90 connected between said anode and said filament, one of said condensers being of much greater capacity than the other and a receiving device connected across the terminals of the condenser of least capacity.

95. 3. A receiving arrangement for electrical oscillations comprising a source of electrical oscillations, a plurality of thermionic valves each having a filament, a grid and an anode, and a battery, each of said filaments being connected together and to the negative pole of said battery, oscillatory anode circuits 100 comprising inductances connected between the anode and positive pole of said battery, and a number of pairs of condensers connected between the anodes and filaments of each valve except the last, the junction point of the condensers being connected to the next valve in the series and a receiving device connected in the anode circuit of said 105 last valve.

110. 4. A receiving arrangement for electrical oscillations comprising a source of trains of high frequency electrical oscillations, a thermionic valve having a filament grid and anode, a battery having its negative terminal connected to the filament of said valve, an oscillatory anode circuit comprising an inductance between the positive pole of said battery and said anode, two 115

120. 4. A receiving arrangement for electrical oscillations comprising a source of trains of high frequency electrical oscillations, a thermionic valve having a filament grid and anode, a battery having its negative terminal connected to the filament of said valve, an oscillatory anode circuit comprising an inductance between the positive pole of said battery and said anode, two 125

130. 4. A receiving arrangement for electrical oscillations comprising a source of trains of high frequency electrical oscillations, a thermionic valve having a filament grid and anode, a battery having its negative terminal connected to the filament of said valve, an oscillatory anode circuit comprising an inductance between the positive pole of said battery and said anode, two 130

condensers in series connected between said anode and said filament and a receiving device responsive only to audio-frequency oscillations connected across the terminals of one of said condensers, the values of the inductance and condensers being so selected as to give a high inductance or capacitance effect and a low positive effect so as to enable oscillations of the frequency of the trains of impulses to be detected on said receiving device due to a cumulative change of voltage across its terminals being created by a train of oscillations and dissipated between trains.

5. A receiving arrangement for electrical oscillations comprising a source of electrical oscillations, a thermionic valve having a filament, a grid and an anode, a circuit connecting said source of electrical oscillations between said filament and said grid, a battery, an oscillatory anode circuit comprising an inductive resistance, connected between said battery and said anode, the other terminal of said battery being connected to said filament, and two condensers in series connected between said anode and said filament and a receiving device connected across the terminals of one of said condensers, the value of said inductive resistance and the capacity of said condensers being so chosen that the frequency of the anode circuit is comparable with the frequency of the received oscillations so that these can be amplified without change.

6. A receiving arrangement for electrical oscillations, a thermionic valve having a filament, a grid and an anode, a circuit connecting said source of electrical oscillations between said filament and said grid, a battery, an oscillatory anode circuit comprising an inductive resistance, connected between said battery and said anode, the other terminal of said battery being connected to said filament, and two condensers in series connected between said anode and said filament and a receiving device connected across the terminals of one of said condensers the value of the resistance of said inductive resistance being comparable with the resistance between the anode and the filament and the inductance effect is low compared with the capacitance.

7. A receiving arrangement for electrical oscillations comprising a source of electrical oscillations, a thermionic valve having a filament a grid and an anode, a circuit connecting said source of electrical oscillations between said filament and said grid, a battery, an oscillatory anode circuit comprising an inductive resistance, connected between said battery and said anode, the other terminal of said battery being connected to said filament, and two condensers in series connected between said anode and said filament and a receiving device connected across the terminals of one of said condensers, the frequency

of the valve circuits being adjusted to be equal to or a multiple of that of the received oscillations.

8. A receiving circuit for electrical oscillations comprising a number of valves arranged in cascade with the filament connected together in which the anode circuits for two valves include an inductance while between the anode and the filament of each valve are two condensers in series, the junction point of the condensers of said valves being connected to the grid of the next succeeding valve, characterized in that the anode circuits of the two valves are so arranged as to exert a mutual effect on each other.

9. A receiving circuit for electrical oscillations comprising a number of valves arranged in cascade with the filaments connected together in which the anode circuits for two valves include an inductance while between the anode and the filament of each valve are two condensers in series, the junction point of the condensers of said valves being connected to the grid of the next succeeding valve, characterized in that the anode circuits of the two valves are so arranged as to exert a mutual effect on each other, and are tuned to the same frequency as the applied oscillations whereby continuous oscillations may be detected by means of beats.

10. A receiving circuit for electrical oscillations comprising a number of valves arranged in cascade with the filaments connected together in which the anode circuits for two valves include an inductance while between the anode and the filament of each valve are two condensers in series, the junction point of the condensers of said valves being connected to the grid of the next succeeding valve, characterized in that the anode circuits of the two valves are so arranged as to exert a mutual effect on the other, being closely coupled together adjusting means being provided whereby the degree of coupling can be varied at will.

11. A receiving arrangement for electrical oscillations comprising a source of electrical oscillations, a thermionic valve having a filament a grid and an anode, a circuit connecting said source of electrical oscillations between said filament and said grid, a battery, an oscillatory anode circuit comprising an inductive resistance, connected between said battery and said anode, the other terminal of said battery being connected to said filament, and two condensers in series connected between said anode and said filament and a receiving device connected across the terminals of one of said condensers, and means for altering the resistance in the anode circuit.

12. A receiving arrangement for electrical oscillations comprising a source of electrical
